US00D766250S

(12) **United States Design Patent** (10) **Patent No.:** **US D766,250 S**
Lukic et al. (45) **Date of Patent:** **** Sep. 13, 2016**

- (54) **INPUT DEVICE FOR INTEGRATING A PHYSICAL AND VIRTUAL INTERFACE**
- (71) Applicant: **Logitech Europe S.A.**, Lausanne (CH)
- (72) Inventors: **Branko Lukic**, Menlo Park, CA (US); **Steven Takayama**, Atherton, CA (US)
- (73) Assignee: **Logitech Europe S.A.**, Lausanne (CH)
- (**) Term: **14 Years**
- (21) Appl. No.: **29/523,876**
- (22) Filed: **Apr. 14, 2015**
- (51) LOC (10) Cl. **14-02**
- (52) U.S. Cl. **USPC D14/455**
- (58) **Field of Classification Search**
 USPC ..... D14/391-393, 396, 320, 247, 455, 457; D18/1, 2, 6, 7; 200/5 A, 5 R, 6 A, 6 R; 178/17 A, 17 C; 235/145 A, 145 R; 341/22, 23, 160, 168; 400/472, 400/484-486, 488, 489, 492; 361/680; 345/168
 CPC G06F 3/0216; G06F 3/0231

(57) **CLAIM**

The ornamental design for an input device for integrating a physical and virtual interface, as shown and described.

DESCRIPTION

FIG. 1 is a perspective view of an input device for integrating a physical and virtual interface showing my new design; FIG. 2 is a perspective view thereof; FIG. 3 is a top plan view thereof; FIG. 4 is a bottom plan view thereof; FIG. 5 is a front elevational view thereof; FIG. 6 is a rear elevational view thereof; FIG. 7 is a left side elevational view thereof; and, FIG. 8 is a right side elevational view thereof. The broken lines shown represent unclaimed subject matter and form no part of the claimed design.
